UNITED STATES PATENT OFFICE.

JAMES SWAN, OF SEYMOUR, CONNECTICUT.

DESIGN FOR A TOOL-HANDLE.

SPECIFICATION forming part of Design No. 28,419, dated March 29, 1898.

Application filed February 23, 1898. Serial No. 671,386. Term of patent 14 years.

To all whom it may concern:

Be it known that I, JAMES SWAN, a citizen of the United States, residing at Seymour, county of New Haven, State of Connecticut, have invented and produced a new and original Design for a Tool-Handle, of which the following is a specification, reference being had to the accompanying drawings, forming part thereof.

Figure 1 is an elevation of a tool-handle embodying my design, and Fig. 2 is a cross-section thereof.

The leading feature of my design consists of a tool-handle having the surface of its gripping portion made polygonal in cross-section—that is, having a number of flat sides, said sides being arranged spirally with relation to the axis of the handle, and said planes lying at obtuse angles to each other, as seen in cross-section.

A denotes the gripping portion of the handle. The surface of the gripping portion is ornamented by a series of flat sides *a*, arranged spirally with relation to the axis of the handle. These sides lie at obtuse angles to each other, as seen in cross-section, the points of intersection of said sides being indicated by *b*, the whole imparting to said gripping portion the appearance of a spiral prism. 25

What I claim is—

The design for a tool-handle substantially as shown and described.

In testimony whereof I affix my signature in presence of two witnesses.

JAMES SWAN.
